UNITED STATES PATENT OFFICE

98,010

DESIGN FOR A BOX OR SIMILAR CONTAINER

Connie Lean, New York, N. Y.

Application June 6, 1935, Serial No. 57,166

Term of patent 7 years

To all whom it may concern:

Be it known that I, Connie Lean, a citizen of the United States, residing in New York, in the county of New York and State of New York, have invented a new, original, and ornamental Design for a Box or Similar Container, of which the following is a specification, reference being had to the accompanying drawing, forming part thereof.

In the drawing:

Fig. 1 is a perspective view of a box or similar container, with the lid in position on the body of the container;

Fig. 2 is a plan view of the lid illustrated in Fig. 1;

Fig. 3 is a front elevation of the parts, as would be seen from the front of Fig. 1.

I claim:

The ornamental design for a box or similar container, as shown.

CONNIE LEAN.
